UNITED STATES PATENT OFFICE.

WILLIAM C. McINTIRE, OF WASHINGTON, DISTRICT OF COLUMBIA.

DRAFT-RIGGING FOR RAILROAD-CARS.

SPECIFICATION forming part of Letters Patent No. 715,121, dated December 2, 1902.

Application filed May 31, 1902. Serial No. 109,717. (No model.)

To all whom it may concern:

Be it known that I, WILLIAM CRANCH McINTIRE, a citizen of the United States, residing at Washington, District of Columbia, 5 have invented certain new and useful Improvements in Draft-Rigging for Railroad-Cars; and I do hereby declare the following to be a full, clear, and exact description of the invention, such as will enable others skilled in the art to which it appertains to make and use the same.

My invention relates to certain new and useful improvements in draw-bar or draft-rigging attachments for railroad-cars, and 15 particularly to that class in which coil-springs are employed to take up the shocks resulting from the bumping or pulling actions and as fully illustrated and described in Letters Patent No. 666,969, granted to Thomas L. 20 McKeen on the 28th day of January, 1901. In draft-riggings of the class referred to the springs are used single or in tandem and sometimes in triple arrangement, accordingly as they are designed for use with cars of increased weight, and as the weight of cars has 25 been materially increased under the rules of the Master Car-Builders' Association it has been found difficult, if not impossible, to provide springs having the necessary capacity 30 to resist the bumping and pulling strains to which they are necessarily subjected. This difficulty has been overcome to some extent by the adoption of what is known as "frictional" draft-rigging appliances; but the employment of such devices involves increased 35 cost of manufacture, a greater number of parts and correspondingly greater difficulty in assembling the several parts, and in making repairs when needed.

40 My invention has for its object to adapt the ordinary coil-spring draft-rigging construction for use with cars of greater weight than they can be successfully used with according to their present construction and operation; 45 and with this end in view my invention consists, broadly, in combining with a coil spring or springs means for winding up or torsionally straining the spring or springs at the same time that they are subjected to longitudinal 50 stress, so that their power of resistance is increased gradually during the bumping or pulling strains to which they are subjected.

In order that those skilled in the art to which my invention appertains may know how to make my improved draft-rigging and 55 to fully understand its operation and advantages, I will proceed to describe the same, referring to the accompanying drawings, in which—

Figure 1 is a vertical longitudinal section 60 taken centrally of the side sills and draft-timbers of the construction shown and described in the Letters Patent hereinbefore referred to and with my improvement applied thereto. Fig. 2 is a transverse section 65 on the line *x* *x* of Fig. 1. Fig. 3 is a horizontal section taken on the line *y* *y* of Fig. 1. Fig. 4 is an enlarged perspective of one end 70 of one of the cheek-plates or housings, and Fig. 5 is a perspective view of one of the 75 spring-followers.

Similar letters of reference denote like parts in the several figures of the drawings.

A represents the longitudinal car-sills, B the subsills, and C the end sill, of ordinary 75 construction.

D is the shank of the draw-head, to which is secured the yoke E, within which are arranged single or tandem coil-springs F, as 80 may be desired.

G represents spring-followers located at each end of the spring F, and H represents housings or cheek-plates secured in the ordinary manner to the longitudinal sills A and subsills B.

I and I' are carry-plates secured by suitable bolts I' to vertical lugs I² on the cheek-plates.

K is the filler or bridge of the yoke.

L represents end stops or vertical ribs on the cheek-plates.

M is a central rib or stop, and N represents intermediate stops adapted to limit the longitudinal movements of the spring-followers G, all of substantially the construction shown and described in the Letters Patent hereinbefore referred to.

I will now proceed to describe one manner of applying my invention to the construction referred to.

The spring-followers G are circular in form 100 and are provided with diametric grooves or recesses O, adapted to receive inwardly-projecting longitudinal ribs P on the cheek-plates H. These ribs P, on opposite sides of the fol-

lowers G, trend helically in order that the said followers in their longitudinal movements shall be caused to rotate or oscillate. The ends F' of the coil-springs F are turned at 5 about right angles to the end coils and are passed into or through corresponding channels or pockets Q (see Fig. 5) in the spring-followers G.

All other parts shown and not described are 10 of the construction shown and described in the Letters Patent hereinbefore referred to.

From the construction described it will be seen that when a buffing strain is exerted the forward end followers are forced rearward, 15 while the rear end followers are held against movement by their respective vertical stops on the cheek-plates and the relation between the ribs P on the said plates and the grooves or recesses O in the followers, and as the forward end followers move rearward to compress the springs F they are caused to rotate or oscillate, through the medium of the longitudinal helical ribs P, on the cheek-plates and the diametric grooves O of the followers, 20 and as the ends F' of the springs are connected, as described, with the followers said springs are twisted or wound up gradually and progressively as the followers continue in their longitudinal movement. Said fol- 25 lowers meet not only the resistance resulting from the compression of the coils of the spring, but also the resistance resulting from the torsional strain exerted upon the same. It will also be seen that the spring resistance neces- 30 sarily and gradually increases as the forward end followers continue their longitudinal movement rearward, so that the nearer they approach to the limit of longitudinal compression the stronger the springs become 35 in their power of resistance.

Under a pulling strain the forward end followers are supported against their respective stops on the cheek-plates, and the rear end followers are caused to travel longitudinally 40 and to rotate or oscillate in the same manner as already described with reference to the forward end followers, and the springs are compressed and subjected to torsional strain in the same manner.

While I have shown a tandem arrangement 45 of springs and followers, it will be understood that the same principle of construction and operation may be applied to a single-spring construction and likewise to a construction involving more than two springs in tandem or other arrangement. It will also be understood that in lieu of the ribs P on the cheek-plates and the diametric channels or grooves O in the spring-followers said construction 55 may be reversed and the ribs may be formed on the followers and helical grooves provided in the cheek-plates.

Any other mechanical construction may be employed which is adapted to produce a twisting or torsional strain upon the coil spring or 65 springs during longitudinal compression of

the same, and any and all details of construction with reference to means for this purpose or to the cheek-plates or housings, draw-bar yoke, and spring-followers may be varied 70 without departing from the spirit of my invention, which resides in the broad idea of combining with the spring or springs adapted to receive the bumping or pulling strains suitable means for winding up or subjecting 75 the spring or springs to torsional strain during their longitudinal or compressive movement.

While I have shown the usual arrangement of exterior and interior springs and with the 80 exterior spring only adapted for torsional strain, it will be understood that both springs may be adapted to similar action.

While my invention is especially designed 85 for use in connection with draft-rigging appliances for railroad-cars, it will be readily understood that the generic principle of said invention may be employed in any other construction where it may be desired to increase the spring resistance during longitudinal compression—as, for instance, in depot or yard “bumping - posts” and in mechanism employed to take up the recoil of gun-carriages.

What I claim as new, and desire to secure by Letters Patent, is—

1. In a draft-rigging, in combination with the springs and suitable external supports between the same and the draft-timbers, revolvable end followers connected with each end of the springs and located within the spring-supports; and means for causing the end followers to move longitudinally and rotatively, substantially as and for the purpose set forth. 95

2. In a draft-rigging, in combination with the draft-timbers and housings secured thereto and adapted to support the springs, followers connected with the ends of the springs and means intermediate of the followers and the spring-housings for rotating the followers during their longitudinal movement, substantially as set forth. 105

3. In a draft-rigging for railroad-cars in combination with the draw-bar yoke and coiled spring or springs, rotatable end followers connected with the spring or springs, and means 115 for causing the end followers to rotate and also travel longitudinally, substantially as and for the purpose set forth.

4. In a draft-rigging for railroad-cars, in combination with the draft-timbers and housings secured thereto, and the draw-bar yoke, springs and spring-followers, whereby the springs may be subjected to compression in a longitudinal direction, means for subjecting the springs to torsional strain coincidently 125 with their longitudinal compression, substantially as and for the purpose set forth.

5. In a draft-rigging attachment for railroad-cars, in combination with the draft-timbers and the housings or cheek-plates secured 130 thereto and provided with vertical ribs or stops, and longitudinal helical ribs, one or

more coil-springs and end followers arranged within the draw-bar yoke, the spring-termi-
nals extended longitudinally and seated within the followers, and the followers provided

5 with channels or grooves to receive the heli-
cal ribs of the housings or cheek-plates, sub-
stantially as and for the purpose set forth.

In testimony whereof I affix my signature
in presence of two witnesses.

WM. C. MCINTIRE.
